UNITED STATES PATENT OFFICE.

GEORGE H. PINNEY, OF SOUTH MANCHESTER, CONNECTICUT.

DESIGN FOR A SPOON OR SIMILAR ARTICLE.

Application filed October 28, 1922. Serial No. 4,152. Term of patent 7 years.

To all whom it may concern:

Be it known that I, GEORGE H. PINNEY, a citizen of the United States, and a resident of South Manchester, in the county of Hartford and State of Connecticut, have invented a new, original, and ornamental Design for Spoons or Similar Articles, of which the following is a specification, reference being had to the accompanying drawing, forming part hereof, in which—

Figure 1 is a view of the front of a spoon,

or similar article showing my new design.

Figure 2 is a back view of the handle.

Figure 3 is a view, scale enlarged, of a portion of said handle.

Figure 4 is a view in section on plane denoted by the dotted line 4—4 of Figure 3.

I claim:

The ornamental design for a spoon or similar article as shown.

GEORGE H. PINNEY.
